ATTORNEY.

UNITED STATES PATENT OFFICE.

SAMPSON TRASK, OF SAN FRANCISCO, CALIFORNIA

ATOMIZER.

1,113,069.

Specification of Letters Patent. Patented Oct. 6, 1914.

Application filed April 16, 1913. Serial No. 761,607.

To all whom it may concern:

Be it known that I, SAMPSON TRASK, a citizen of the United States, residing at San Francisco, in the county of San Francisco and State of California, have invented a new and useful Atomizer, of which the following is a specification in such full and clear terms as will enable those skilled in the art to construct and use the same.

10 This invention relates to a pocket atomizer, the object of which is to enable the user to spray determinate quantities of the liquid into the nose or eyes whenever necessary.

15 Another object of the invention is to simplify the construction of the atomizer to such an extent as to eliminate all unnecessary parts, especially dispensing with valves.

Another object of the invention is to make 20 an atomizer of a convenient shape for the pocket.

Another object of the invention is to make an atomizer which will easily measure the dosage, and which can be used to spread the 25 nostril thus making it more effective.

Another object of the invention is to make an atomizer which is of such shape as to easily stand alone and which will be provided with means to retain it in the pocket.

30 Other objects of the invention will appear as the description proceeds.

I am aware that there are many modifications of this invention, but one of the embodiments thereof is shown in the drawings 35 in which the same reference numeral is applied to the same portion throughout.

Figure 1 is a plan view of the atomizer, Fig. 2 is a plan view in section, Fig. 3 is a central vertical sectional view thereof, Fig. 40 4 is a side view of the sprayer, Fig. 5 is a plan view in section of a slightly modified form of capillary supply tube, and Fig. 6 is a vertical sectional view of the modified spray tube having a larger number of the 45 capillary tubes.

The numeral 1 is applied to the receptacle in which the liquid is placed, said receptacle having grooves formed therein at 2 and 3 to hold rubber rings 4 and 5 in place. The 50 ring 4 is made stiff enough to hold the receptacle upright on a flat surface and the

ring 5 prevents the receptacle from falling out of the pocket.

The receptacle for the liquid is closed by means of the stopper 6, which stopper has its upper portion 7 formed into a bulb. The stopper is made of a grade of rubber solid enough to hold the tube 8 firmly in place when inserted therein, and said tube carries a cone shaped head 9 which has a series of 66 capillary tubes or passage ways 10 formed therein. There may be such a number of these openings as is deemed necessary to supply the required dosage. It will be noted that in order to operate as intended the tubes 10 must be small enough to retain the liquid even when turned upside down as a capillary tube does.

Figs. 5 and 6 illustrate a modified form of the invention in which the conical head is replaced by small glass tubes.

The numeral 12 indicates the central tube to which the bulb is connected. This central tube has four capillary tubes 13 connected therewith, said tubes terminating adjacent 75 the end of the tube 12, whereby any liquid contained in the tubes 13 will be discharged therefrom in a fine spray.

It will be observed that while the series of tubes necessary to hold the required dosage 80 may be more or less in number, that the head necessary to carry said tubes is of an advantageous shape in that it may be used to spread the nostril in using the atomizer, while if the atomizer is used for spraying 85 the eye the shape of the head is not a disadvantage.

Having thus described my invention what I claim as new and desire to secure by Letters Patent of the United States, is as follows, modifications within the scope of the claims being expressly reserved:

1. In an atomizer, a tube, a bulb carried on one end of said tube, and a conical atomizer head on the other end of said tube, 95 said head having a plurality of relatively short capillary tubes for the retention of a liquid.

2. An atomizer comprising a receptacle and a removable atomizer closely fitting in 100 the open end of said receptacle, said atomizer comprising a tube having a bulb on

one end thereof forming a stopper for the receptacle, and an atomizer head on the other end of said tube, said head having a plurality of relatively short capillary passages therein.

In testimony whereof I have hereunto set my hand this 29th day of March A. D. 1913,

in the presence of the two subscribing witnesses.

SAMPSON TRASK.

Witnesses:

HENRY B. LISTER,
CARLOS P. GRIFFIN.
